CUTTER AND CUTTER HOLDER FOR TAPS

Original Filed April 25, 1927

UNITED STATES PATENT OFFICE

SAMUEL F. NEWMAN, OF WAYNESBORO, PENNSYLVANIA, ASSIGNOR TO LANDIS MACHINE COMPANY, OF WAYNESBORO, PENNSYLVANIA, A CORPORATION OF PENNSYLVANIA

CUTTER AND CUTTER HOLDER FOR TAPS

Original application filed April 25, 1927, Serial No. 186,470. Divided and this application filed February 12, 1931. Serial No. 515,366.

This invention relates to thread cutters for taps and to means for holding them and particularly to thread cutting devices for collapsible taps and is a division of my application Serial No. 186,470, filed April 25, 1927, for collapsible taps.

An object of the invention is to provide new and improved thread cutters which re-cede during the process of cutting a thread and with new and improved holders for such cutters.

Another object is to provide removable thread producing cutters in which separable holders are provided so as to eliminate the necessity of providing new working or sliding surfaces on the cutters themselves.

In constructions heretofore known the thread cutting chaser was in sliding contact with one of the taper producing elements in the tap so that the seating surfaces of the chaser become worn and hence soon failed to produce accurate threads. An object of the present invention is to eliminate such defects so that the life of the chasers will be increased and more accurate threads produced.

A still further object is to provide new retracting means for the chaser or cutters and means for collapsing the chasers when thread of the desired length has been cut.

Further objects and advantages will become apparent as the description proceeds.

Referring to the accompanying drawing, which is made a part hereof and on which similar reference characters indicate similar parts,

Figure 1 is a longitudinal section of a tap showing the thread cutting elements, holders and plunger mounted therein;

Figure 2 is a face view of a tap showing the cutters and holders in assembled position;

Figure 3 is a front view of one form of holder;

Figure 4, a side view of the same;

Figures 5 and 6 are front and side views respectively of the chaser or cutter used with the holder shown in Figures 3 and 4;

Figures 7 and 8 are front and side views respectively of a modified form of chaser holder, and

Figures 9 and 10 are front and side views

respectively of the chaser used in holders shown in Figures 7 and 8.

In the drawing numeral 10 indicates the body portion of a tap having a removable head 11 secured thereon, as by means of bolts 12. The head 11 is provided with radial slots 13 in which are positioned radially movable thread cutting devices 14. Within the body portion 10 is axially slideable a plunger 15 having a head 16 removably secured thereto by means of a bolt 17. The bolt is threaded at its forward end in the head 16 and has an enlarged end 18 seated in a socket in the end of the plunger 15 and held in said socket by means of a spring 19. A front plate 20 is held on the head 11 by means of bolts 21.

The head 16 is provided with slots having tongues 22 around which engage corresponding slots 23 of chaser holding blocks 24. The holders 24 are likewise provided with projections 25 having surfaces 26 upon which the cutters 14 are seated. A tongue 28 extends in from a back portion 29 of the holder which tongue engages in a slot 30 in the back of the cutter. The cutter is held against radial movement by means of the tongue 28. As will be seen from the assembled view of Figure 1 there is no relative axial movement between the cutters 14 and the holders 24, the holders and cutters are, however, positioned radially by means of the cam surfaces 31 on the end of the head portion 16. Since there is no relative movement between the cutters and holders there will be no wear on the engaging surfaces.

In Figures 7 to 10 inclusive are shown modified forms of holders 32 and cutters 33. In this form the base 34 of the holder engages the beveled portion 31 of the head 16 and the tongue 22 of the head engages the slot 35 of the holder. There is provided, however, a tongue portion 36 which cooperates with the surface 37 of the holder and holds the cutter in position. The upper back portion 38 of the holder is threaded at 39 and the cutter 33 has its back cut out as shown at 40 to receive a screw 27 which serves to hold the cutter against outward or radial movement. With the holders and cutters shown in Figures 7 to 10 inclusive the cutters

may be removed and replaced without removing the end plate 20. This provides a simpler means of assembly. The plunger 15 is controlled by the work coming in contact with a plate 41 which plate controls radial position of a slide 42 as is more fully described in the parent application of which this is a division.

In operation the plunger 15 is moved to the right as the ring 41 contacts with the work 43. This movement to the right gradually retracts the cutters 14 as the inner beveled edges of the holders slide on the corresponding beveled portions 31 of the head 16. This positions the chaser to cut the desired taper on the thread. By rotating the bolt 17 as by means of a wrench inserted in the hexagonal socket 44 the radial position of the cutters 14 may be varied to adjust them for work of different diameters. With the forms of cutters and holders shown in Figures 7 to 10 in order to replace the cutters screws 27 may be removed after which the cutters may be lifted out of their holders 32 and new ones positioned therein. With the cutters and holders shown in Figures 3 to 6 inclusive it is necessary to remove the plate 20 after which the cutters may be slid axially off the holders and new ones positioned thereon. In both forms of cutters and holders there is no relative axial sliding between the cutters and the holders, consequently the engaging surfaces are not worn.

It will be obvious to those skilled in the art that various changes may be made in my device without departing from the spirit of the invention and therefore I do not limit myself to what is shown in the drawing and described in the specification, but only as indicated by the appended claim.

Having thus fully described my said invention, what I claim as new and desire to secure by Letters Patent, is:

In a collapsible tap in combination, a chaser holder and a chaser, the chaser having parallel cutting serrations on one face and a cut away portion in the opposite face to provide a tongue and a chaser holder having two parallel extending ribs of unequal length and a groove therebetween for receiving said tongue the longer of said ribs having a threaded opening extending through the periphery of the tap longitudinally of said longer rib and at an angle to the bottom of said groove, and a screw threaded through said opening and engaging a notch in the chaser to secure it to the holder, substantially as set forth.

In witness whereof, I have hereunto set my hand at Waynesboro, Pennsylvania, this ninth day of February, A. D. nineteen hundred and thirty-one.

SAMUEL F. NEWMAN.
